CAPACITY LOADING SYSTEM

Joseph W. Milnor, Maplewood, N. J., assignor to
The Western Union Telegraph Company, New
York, N. Y., a corporation of New York

Application December 23, 1941, Serial No. 424,208

3 Claims. (Cl. 178—44)

This invention relates to electrical transmission systems comprising sections of cable interspersed with open wire line sections. The principal object of my invention is the reduction of attenuation in the transmission at high frequencies over such mixed cable and open wire circuits by a method of loading the open wire sections. Spaced condensers effect a reduction of the impedance of the open wire until it matches that of the cable, thereby eliminating the reflection losses which occur at the junctions of the open wire and cable.

Transmission lines for high frequencies usually consist predominantly of open wire having an impedance of approximately 600 ohms with a small negative angle and characterized by relatively low attenuation. The open wire is normally interspersed with occasional short sections of cable necessitated by river crossings, city entrance purposes, and the like. These cable sections are detrimental to transmission in that they not only have higher attenuation but since their impedance is of the order of 140 ohms, serious reflections occur at the junctions of the two types of conductor. To reduce this attenuation it is often necessary to load the cable sections, at the same time making the impedance the same as that of the open wire line in order to prevent reflections at the junctions. However, the spacing of the loading coils grows smaller as the frequency increases so that for frequencies of the order of 30 kc., it may become as low as 900 feet. To provide loading coils at such frequent intervals becomes very expensive, particularly in the case of underground cables, where manholes must be provided. In many cases it is physically impossible to locate manholes at the proper locations.

Since a loaded cable terminating at mid section presents a resistive impedance rising with frequency, a further requirement of such loading systems is the necessity of modifying this impedance by means of special fractional sizes of coils for insertion near circuit terminals and near the junctions of the cable and open wire. By this refinement a constant impedance is obtained for the cable closely matching that of the open wire under the conditions of irregular cable lengths found in practice. One system for terminating such loaded cables is disclosed in Patent No. 2,096,401.

As the frequencies employed become higher, the cost of loading increases rapidly so that often it is more economical to omit the loading and to space the repeaters more closely instead. How-

ever, the impedance inequality at junctions of cable and open wire cause a severe reflection loss which may be aggravated by multiple reflections. This loss, because it is often irregular with frequency, cannot be satisfactorily recovered by means of repeaters, and furthermore, problems of equalization and of selective crosstalk are introduced. Efforts have been made to reduce this reflection loss by employing transformers or other impedance transforming devices for joining the two types of conductors. These devices, however, are limited in their frequency range such that if a satisfactory match is provided at high frequencies, an excessive loss may be introduced at voice frequencies or vice versa. In addition, the devices usually necessitate a direct or a condenser connection between the two conductors of the pair. This connection interferes with telegraph or other direct current utilization of the conductors.

The system of loading disclosed herein differs from the one just described in that it is designed for particular application to situations where relatively short lengths of open wire are located between sections of cable. It is most effective when the cable sections are very long but it is useful also where short cable sections are separated by short sections of open wire. By the method disclosed herein, the impedance of the open wire is reduced by means of capacity loading of the open wire line so that it approximately matches that of the associated cable and thus prevents the occurrences of reflections. The loading is accomplished by means of small condensers connected between the two wires of the pair at intervals analogous to those employed for loading coils in cable. For use near each end, a series of fractional sizes of condensers are desirable. In certain cases a compromise arrangement may be used, that is, the open wire will be capacity loaded only sufficiently to approach the impedance of the cable since the reflection loss is not large for relatively small impedance discrepancies. This will permit a reduction in the size of condensers with consequent reduction in attenuation both to carrier and speech currents and to the physical telegraph circuits.

In the accompanying drawing, Figure 1 is an impedance-frequency diagram for a composite circuit of open wire and non-loaded cable sections showing the resistance and reactance components; the change in said components after loading and the effect of terminat-

ing a loaded line at mid-section, in this case mid-condenser;

Figure 2 is a diagram illustrating a non-loaded cable to which is connected a length of capacity loaded open wire terminating at mid-condenser and provide with a special terminating section;

Figure 3 is a diagram showing essential details in more specific form; and

Figure 4 illustrates diagrammatically the normal attenuations per mile in No. 9 Cu open wire and for No. 13 gage cable and to illustrate the benefits of the loading system according to the present invention the two top curves show the attenuation loss caused by the insertion of a length of open wire in a long section of non-loaded cable both before and after capacity loading of the open wire section, while the irregular curve shows in particular the serious loss caused by multiple reflections.

The manner of designing a capacity loading system for open wire so that its impedance will be the same as that of an associated cable section will now be illustrated. For this example No. 9 Cu open wire will be loaded to match the impedance of No. 13 gauge cable although the same development will apply to other sizes and types of conductors. The characteristics of these conductors per mile are:

No. 13 ga. cable $C = .062 \text{ mf.}$, $L = .0012 \text{ h.}$
No. 9 Cu open wire (12' spacing) $C = .0084 \text{ mf.}$, $L = .0036 \text{ h.}$

For convenience the capacity of the open wire will be neglected in the following calculation of condenser sizes.

Since $\sqrt{L/C}$ for the open wire must be made approximately equal to $\sqrt{L/C}$ for the cable:

$$\frac{.0036}{C_{ow}} = \frac{.0012}{.062}$$

whence $C_{ow} = .186 \text{ mf./mi.}$; that is, .186 mf. should be added to each mile of open wire to make its nominal impedance the same as that of the cable.

From conventional loaded line theory it is known that a satisfactory approach to the effect of a smooth loaded line may be obtained with lumped loading if the loading to be added is equidistantly spaced, at the rate of four equal parts per wave length of the highest frequency to be transmitted. With a wave length for the loaded open wire equal to $1/f \cdot \sqrt{LC}$, examples for 7,000, 30,000 and 50,000 cycles have been computed, as follows:

Frequency	λ wave length, mi.	Nominal loading section $\lambda/4$		
		Length, mi.	Condensers, mf.	Wire inductance, h.
7,000	5.62	1.380	.258	.00497
30,000	1.29	.322	.060	.00116
50,000	.78	.195	.038	.00072

That is, as an example, to load a length of open wire situated between lengths of No. 13 ga. cable so as to have the same impedance as the cable and to transmit frequencies up to 30,000 cycles, condensers of .060 mf. should be connected between the two wires of the pair at intervals of .322 mile.

The nominal impedance of No. 9 Cu open wire and of No. 13 gauge non-loaded cable are indicated by the solid and the dashed curves respec-

tively of Fig. 1 which gives both the resistance and reactance components. After loading, the relatively high resistance component of the open wire becomes nominally the same as that of the cable. However, when a loaded line is terminated at mid-section, or mid-shunt, that is in the case of the capacity loaded open wire a full section of line and a $1/2$ size loading condenser, while the reactance component is small, the resistance increases with frequency, as indicated by the long dash curve. It becomes desirable, therefore, to provide a special terminating arrangement for both ends of the capacity loaded line section which will render this resistance approximately constant with frequency and of the desired nominal value. An analogous system of terminating sections adapted for terminating a loaded cable to provide an impedance matching that of open wire is described in the Patent 2,096,401, previously referred to. For the present capacity loading system, a terminating section can be conveniently derived from a fractional length of open wire in combination with one or two fractional sized condensers, to be located at one end or at both ends of the fractional section.

Figure 2 illustrates a long non-loaded cable to which is connected a length of capacity loaded open wire which terminates at mid-condenser at point 1. Between points 1 and 4 lies a terminating section composed of the fractional line section a and the fractional sized condensers b and d . The manner of determining the size of the two condensers corresponding to the fractional line section a will now be derived. Several combinations will be developed, final choice of any particular condition depending upon the fractional length of line conveniently available at the end of the loaded section and also upon the sizes of available standardized condensers.

The impedance of a long loaded line terminated at mid-shunt, and regarded as a series of n sections having series impedances Z_L and shunt impedances $2Z_C$, may be stated: (see K. S. Johnson, Telephone Transmission Circuits, p 125)

$$Z_1 = \sqrt{\frac{Z_L Z_C}{1 + \frac{1}{4} \frac{Z_L}{Z_C}}}$$

If $Z_L = j\omega L$, and $Z_C = 1/j\omega C$, where $\omega = 2\pi f$ and L and C are the inductance and capacity respectively per unit length of the open wire, then Z_1 becomes

$$\sqrt{L/C} / \sqrt{1 - \frac{\omega^2 LC}{4}}$$

This is the impedance of the loaded open wire line measured at point 1. The impedance of the condenser d is $1/j\omega dC$, and the impedance measured at the point 2 is then:

$$Z_2 = \frac{\frac{1}{j\omega dC} \cdot \frac{\sqrt{L/C}}{\sqrt{1 - \frac{\omega^2 LC}{4}}}}{\frac{1}{j\omega dC} + \frac{\sqrt{L/C}}{\sqrt{1 - \frac{\omega^2 LC}{4}}}}$$

which reduces to:

$$Z_2 = \frac{\sqrt{L/C}}{j\omega dC \sqrt{L/C} + \sqrt{1 - \frac{\omega^2 LC}{4}}}$$

The impedance of the line section a is $j\omega aL$, and the impedance measured at point 3 becomes:

$$Z_3 = j\omega aL + \frac{\sqrt{L/C}}{j\omega dC\sqrt{L/C} + \sqrt{1 - \frac{\omega^2 LC}{4}}}$$

$$= \frac{\sqrt{L/C} - \omega^2 adLC\sqrt{L/C} + j\omega aL\sqrt{1 - \frac{\omega^2 LC}{4}}}{j\omega dC\sqrt{L/C} + \sqrt{1 - \frac{\omega^2 LC}{4}}}$$

The impedance of the condenser b is $1/j\omega bC$, so that the impedance measured at point 4 is:

$$Z_4 = \frac{\frac{1}{j\omega bC} \left[\sqrt{L/C} - \omega^2 dLC\sqrt{L/C} + j\omega aL\sqrt{1 - \frac{\omega^2 LC}{4}} \right]}{j\omega dC\sqrt{L/C} + 1 - \frac{\omega^2 LC}{4}}$$

$$= \frac{\frac{1}{j\omega bC} \left[\sqrt{L/C} - \omega^2 adLC\sqrt{L/C} + j\omega aL\sqrt{1 - \frac{\omega^2 LC}{4}} \right]}{j\omega dC\sqrt{L/C} + 1 - \frac{\omega^2 LC}{4}}$$

$$= \frac{\sqrt{L/C} - \omega^2 abLC\sqrt{L/C} - \omega^2 adLC\sqrt{1 - \frac{\omega^2 LC}{4}} - j\omega a\sqrt{LC}\sqrt{1 - \frac{\omega^2 LC}{4}} - \omega^2 adLC}{(1 - \omega^2 abLC)\sqrt{1 - \frac{\omega^2 LC}{4}} + j\omega\sqrt{LC}(b+d) - j\omega^3 abd(LC)^{3/2}}$$

Making $j\sqrt{LC} = s$, the foregoing becomes:

$$Z_4 = \frac{1 + sa\sqrt{1 + s^2/4} + s^2 ad}{1 + s^2 ab\sqrt{1 + s^2/4} + s(b+d) + s^3 abd}$$

It is desired that Z_4 shall be equal as nearly as practicable to the nominal impedance of the capacity loaded line for all values of s , i. e.

$$Z_4 = \sqrt{L/C}$$

The above expression then becomes:

$$(1 + s^2 ab)\sqrt{1 + s^2/4} + s(b+d) + s^3 abd = \frac{1 + sa\sqrt{1 + s^2/4} + s^2 ad}{1 + s^2 ab\sqrt{1 + s^2/4} + s(b+d) + s^3 abd}$$

Expanding the radical $\sqrt{1 + s^2/4}$:

$$\sqrt{1 + s^2/4} = 1 + s^2/8 - s^4/128 + s^6/1024 \dots$$

and substituting in the preceding expression we have:

$$1 + s(b+d) + s^2(1/8 + ab) + s^3 abc + s^4(a/8b - 1/128) + s^6(1/1024 - a/128b) = \frac{1 + sa + s^2 ad + s^3 a/8 - s^5 a/128}{1 + s^2 ab\sqrt{1 + s^2/4} + s(b+d) + s^3 abd}$$

Equating the algebraic sum of the coefficients of like powers of s to zero for the first two powers:

From s coefficients $a = b + d$

From s^2 coefficients $d - b = 1/8a$

From these equations the values of b and d in terms of a are found to be:

$$b = \frac{8a^2 - 1}{16a}, \quad d = \frac{8a^2 + 1}{16a}$$

If we assume a range of fractional loading sections of open wire a and solve for the corresponding values of b and d , we have:

a	b	d
.354	0	.354
.40	.0438	.3562
.45	.0857	.3635
.50	.1280	.3750
.55	.1613	.3886
.60	.1988	.4042
.65	.2288	.4220
.73	.2760	.4504
.80	.3220	.4780

The foregoing table gives a range of condenser

sizes which may be used to load terminal fractional lengths a of open wire ranging from .354 to .8 of a section length. Below these values the element b becomes negative while above this range the values become inaccurate. The greatest accuracy occurs at the value $a = .73$.

Referring again to Fig. 1, the long dash curve represents the impedance of the open wire loaded for 50 kc. and terminated at mid-shunt, as obtained from the expression—

$$Z_1 = \frac{\sqrt{L/C}}{\sqrt{1 - \frac{LC\omega^2}{4}}}$$

16 After the addition of a terminating section, the loaded open wire will have an impedance as represented by the dot-dash resistance and reactance curves. These curves, computed from the expression for Z_4 for purposes of illustration, correspond to the case where $a = .73$.

It will be noted that the curve for the corrected impedance of the open wire has a satisfactory correspondence to the curve for the cable resistance throughout the working range. The reactance of the open wire is reduced to substantially zero throughout this range. The magnitude of the discrepancy between the reactances of the two conductors is small except at the lower end of the frequency range.

30 Fig. 3 shows the lengths of section and the condenser sizes which should be used to load the open wire for 60 kc., along with the terminating section corresponding to $a = .73$ which gives the dot-dash impedance curves of Fig. 1. In practice, some small modifications of the values b and d are necessary in order to allow for the effect of the resistance and capacity of the open wire which were neglected in the original derivations for the terminating section.

40 In Fig. 4 there is illustrated the normal attenuations per mile for No. 9 Cu open wire and for No. 13 gauge cable and also for the loaded open wire. The attenuation for the loaded case is derived from the well known expression:

Attenuation in db. = $8.68 (R/2 + LG/2C) \sqrt{C/L}$, using the following constants per mile:

Frequency	R ohms	G micromhos
7,000	10.15	2.2×10^{-6}
30,000	18.50	8.4×10^{-6}
50,000	28.00	15.0×10^{-6}

$L = .0036$ henry. $C = .186$ microfarad.

55 In addition, to illustrate the benefits of the loading system herein described, the two top curves show the attenuation loss caused by the insertion of a 5-mile length of open wire in a long section of non-loaded cable, both before and after capacity loading of the open wire section. The irregular curve includes the normal attenuation for 5 miles of open wire and also the more serious loss caused by multiple reflections which in addition to its severity is irregular with frequency. After loading, this irregularity disappears and the attenuation is reduced 7 db. or more from the maximum before encountered. A similar improvement is realized with open line sections of both shorter and longer lengths, but the increased attenuation of the loaded open wire introduces a limit to the length which may be practically loaded. However, the elimination of the reflection peaks with the consequent reduction in crosstalk, equalization, echo, and tele-

70

phone repeater balance problems, may make this method of stabilization of impedance desirable for lengths of included open wire much longer than would be indicated by considerations of attenuation alone.

Since the reflection losses do not become severe until relatively large inequalities in impedance are reached, it is feasible to allow a moderate mismatch between the impedances of the cable and loaded open wire in order to reduce the size of the loading condensers and at the same time reduce the attenuation added to the open wire. In the foregoing case, the impedance of the open wire was made exactly equal to that of the 140 ohm cable. If the impedance of the open wire were, for example, made 200 ohms instead, the size of the condensers would be approximately halved, the added attenuation would be reduced by about one-third, and the resulting reflection losses would not be unacceptable for many less critical situations.

As is common in loading systems, the fractional section of open wire may be built out to a desired length by means of small inductance coils. Single condensers connected between the two wires of the pair have been shown. Such condensers if too large tend to produce interference between grounded telegraph circuits worked on the individual conductors. This interference can be prevented if two condensers of double size with their junction grounded are employed instead. A portion of the desired capacity increase can be obtained if desired through closer spacing of the wires or through higher capacity insulators.

The foregoing description discloses a method of capacity loading of open wire line sections designed to impart to the open wire the same impedance characteristics as the associated long cable sections, thereby eliminating the severe reflection losses which occur at junctions of these two types of conductor. A terminating loading section has also been developed to serve as a connecting element between the loaded line and the non-loaded cable. While the loading arrangement described herein has particular application to relatively short lengths of open wire contained within long sections of non-loaded cable, other applications of this organization will occur where benefits in the reduction of selective crosstalk, echoes, and the relief of equalizing and balancing problems may be realized.

I claim:

1. In a signaling transmission system comprising in sequence along its length, non-loaded cable sections and open wire line pairs of conductors provided with unit condensers of suitable capacity in shunt to the pairs of open wire conductors at regular predetermined unit intervals to thereby reduce the relative impedance characteristics of said open wire pairs to substantially equal the lower impedance characteristics of said cable sections connected thereto, one of said open line sections terminating at a mid-unit interval and means supplementing said mid-unit condenser for maintaining the impedance of the open wire section approximately constant under varying frequency conditions, said means comprising the interposition of a fractional length of a conductor pair shunted by suitable fractional sized condensers.

2. The combination of a signalling system for a range of frequencies comprising a pair of non-loaded cable conductors joined to a pair of open wire conductors of higher impedance than the cable conductors, unit condensers in shunt to said pair of open wire conductors at regular predetermined intervals and of such value that the impedance of the pair of open wire conductors at the lower end of said range of frequencies is thereby reduced to substantially equal that of the associated cable conductors, said open wire conductors terminating at a full length interval, and a supplemental terminating section for interposition between said two pairs of conductors, comprising a fractional section length of open wire pair shunted by a fractional sized condenser at one or both ends said fractional elements having such values that the impedance of the open wire pairs is rendered substantially equal to that of the cable over the remaining upper end of the range of frequencies.

3. A capacity loading system for transmission lines comprising a series of unit condensers spaced at regular intervals in shunt to said circuit, the final condenser of said series being approximately one-half unit size to produce an impedance irregularity, and a terminating section for said system comprising a fractional interval of line in combination with one or more fractional sized condensers for correcting said impedance irregularity.

JOSEPH W. MILNOR.
